(57) **CLAIM**

The ornamental design for a paper pack with ink tank for printer, as shown and described.

DESCRIPTION

FIG. 1 is a front view of a paper pack with ink tank for printer showing my new design;

FIG. 2 is a rear view thereof;

FIG. 3 is a top plan view thereof;

FIG. 4 is a left side view thereof, the opposite side is not being claimed; and,

FIG. 5 is a perspective view thereof.

The portions shown in broken lines throughout the drawings are for illustrative purposes only and form no part of the claimed design.
